UNITED STATES PATENT OFFICE.

JOSEPH M. KENDALL, OF SAN DIEGO, CALIFORNIA.

CIRCLE-HEAD-WINDOW SHADE.

Application filed March 18, 1926. Serial No. 95,520.

This invention relates to improvements in circle head window shades, and more particularly to shades for windows having a semi-circular section at their top, and which ordinarily is treated separately in equipping such windows with shades.

The object of the invention is to provide a shade which will be of a simple construction, readily installed, and ornamental in appearance.

A further object of the invention is to provide a shade in which plaited material is used, the plaits radiating from the central point of the base, giving what may be termed a "sunburst" effect, adapted to harmonize with plaited draw shades in the rectangular portion of the window below.

Shades constructed in accordance with the present invention may be either permanent or adjustable, both types being herein disclosed.

In the accompanying drawings,

Figure 1 is a view in rear elevation of a shade of the character hereinbefore described.

Figure 2 is an enlarged perspective view showing the details of the shade construction.

Figure 3 is an enlarged end view showing the method of attaching the plaited material to the supporting frame.

Figure 4 is a similar view showing another method of applying the shade material to the frame.

Figure 5 is a view in rear elevation of a shade having adjustable sections.

Figure 6 is an enlarged perspective view showing the details of construction of the shade illustrated in Figure 5.

Figure 7 is an enlarged detail view in vertical section as taken on line 7—7 of Figure 6, showing one curtain section lowered and the other raised; and

Figure 8 is a detail view in vertical section taken on line 8—8 of Figure 7.

A shade of the form shown in Figures 1 to 4, consists generally of a body 1 of suitable shade fabric, fixed to a frame 2, of semi-circular shape, the whole forming a unitary self-sustaining structure adapted to be mounted in the semi-circular portion or head A of a window frame. The frame 2 is of skeleton form, made up of a straight horizontal bar 3, preferably of a light gauge angle iron, which forms the base of the shade, and a round rod 4 bent in semi-circu-

lar form and of a radius slightly less than the radius of the complete shade. The ends of the rod are secured to the bar 3 by passing the threaded ends thereof through holes drilled in the horizontal web of the bar near its ends and securing the same by means of nuts 5 applied to the threaded ends of the rod above and below the web.

The fabric body portion 1 of the shade is fashioned from a sheet of shade cloth, preferably of a relatively stiff grade, which has been subjected to a plaiting process. These plaits for an average sized shade would be about 1½ inches in width, and would extend transversely of the sheet, it being assumed that the plaiting would require a sheet of considerably greater length than width, this latter dimension being equal to the radius of the finished shade.

The shade material in its plaited form is first gathered along one edge with the plaits pressed together, whereupon holes 1^a are punched through the plaits near the gathered end. Midway between the ends of the bar 3, is mounted a central anchor rod 6 of semi-circular shape, of a radius of an inch or so. The ends of this rod are also threaded and adapted to be inserted through holes drilled in the horizontal web of the bar 3 and secured by nuts 7, 7 in somewhat the same manner as the outer semi-circular rod 4. The center of the shade material being anchored in place, the remainder is spread fan-like throughout a semi-circle with the end edges or plaits lying flatwise along the semi-circular rod 4, the material being disposed toward the front so that the rod is concealed, it being assumed that the vertical web of the bar 3 faced toward the front. As a preferable means of securing the end edges of the fabric body flatwise along the bar 3, thin strips of metal 8 are laid along the endmost plaits and either side of the central anchor rod 6, and fastened to the bar 3 by short bolts or screws passing through the ends of the strips, the plaits and the horizontal web of said bar.

It is to be noted that in assembling the fabric on the frame, that the vertical web is considered the front of the shade, so that the fastening strips 8 are applied from the rear and thus are concealed or covered by the plaits. In this way, the metal framework of the shade is quite concealed, thus giving a finished appearance. To further enhance the appearance, a suitable rosette or

medallion 10 may be placed at the center and at the front side of the bar 3, where the plaits converge to a point, thus concealing the mounting at that point as well as adding to the "sunburst" effect.

As a preferred means of attaching the fabric body to the outer rod 4, a strand of thin wire 9 is threaded through the edges of the plaits at several points of contact with the rod and thence wrapped around the rod, this process being carried from plait to plait throughout the length of the rod, as clearly shown in Figure 3.

As disclosed in Figure 4, another method may also be used, namely, that of punching a line of holes as at 1^b through the plaits at the outer edge of the material, and threading the plaits onto the rod, the friction of the material on the rod serving to hold the material in place, after it has been spread.

The shade having thus been assembled, it is mounted in place by securing the ends of the bar 3 to the vertical side frame members of the window sash A, by suitable supporting fixtures, preferably allowing for the removal of the shade so that the window can be cleaned. Thus supported, the body of the shade stands upright closing the semi-circular head of the window without attachment to the window frame except perhaps by a single hook *a* depending from the top of the window frame and engaging the rod 4 to prevent undue strain. The angle bar 3 may also serve as the transverse top support for extensible draw shades for the window section below, these shades being suspended from the bar by cords or wires, and raised or lowered by other cords and pulleys secured to the bar and conveniently concealed behind the vertical front web therof.

As already suggested, a shade of this character may be made so that it can be adjusted, that is to say, lowered and raised to regulate the amount of light admitted through the top semi-circular section of the window. Figures 5 to 8 disclose a preferred construction where such a modification is desired. The essential feature of departure in this construction is the parting of the plaited shade material into two sections or halves 11, 11 which in the closed position, come together in the vertical line, radiant from the center of the shade. Along the parting edges of each adjustable section are flat bars 12 inserted through tubular hems 11^a formed along these edges, the lower ends of these bars having holes 12^a whereby these ride on the central U-shaped pivot rod 13, which in this construction is of a slightly greater radius, and flattened at its top, as shown in Figure 7. These bars 12 serve two purposes, first, to stiffen the edges of the plaited sections, and second, to give the necessary weight, so that the two sections will fall apart and drop down by

gravity into open position, with the plaits folded together on opposite sides of the center.

To afford the shade more stability in its operation, the lower ends of the bars 12, 12 are preferably hinged to a block 14, mounted on the top face of the bar 3, between the ends of the anchor rod 13, suitable hinges 15 being used for this purpose. The block 15 is anchored to the rod by rivets 14^a, and the hinges similarly fixed to the block by rivets 15^a. As clearly shown in Figure 7, the plaited shade material is punched at both ends to provide holes through the rods 13 and 4, which are threaded, the holes in this instance being of ample size so that plaited material will run free over the rods in the opening and closing of the sections.

A suitable arrangement of draw cords 16 and pulleys 17 are used for operating the adjustable sections of the shade, each being preferably controlled separately, although considerable latitude is contemplated in the matter of operation.

Having disclosed the preferred constructions for shades embodying my invention, it is to be understood that I do not wish to be limited to specific details or to any particular application thereof, except in so far as I have set them forth in the appended claims.

I claim as my invention:

1. In a shade for a window of the character described, the combination of a semi-circular supporting frame, and a sheet of plaited shade material gathered along one edge and secured midway the base of said supporting frame with the remaining portion spread fan-like about said frame and secured thereto at its edges.

2. In a shade for a window of the character described, the combination of a frame consisting of a transverse bar and a semi-circular member fixed at its ends to said bar, a body of plaited fabric gathered along one edge and spread fan-like to conform to the shape of said frame, and means for securing the body to said frame.

3. In a shade for a window of the character described, the combination of a semi-circular frame consisting of straight and curvilinear members connected together at their ends, a body of fabric plaited transversely and gathered along one edge, a U-shaped rod passing through holes in the gathered edge of said body and secured to said straight member midway of its ends, the remaining portion of said body being spread in fan-like formation and secured to said frame.

4. In a shade for a window of the character described, the combination of a semi-circular frame consisting of straight and curvilinear members connected together at their ends, a body of fabric plaited trans-

- versely and gathered along one edge, a U-shaped rod passing through holes in the gathered edge of said body and secured to said straight member midway of its ends, 5 said body being spread fan-like about said curvilinear frame member, and means for securing the endmost plaits to said straight member and the intermediate plaits to said curvilinear member.
- 10 5. In a shade for a window of the character described, the combination of a semi-circular frame consisting of straight and curvilinear members connected together at their ends, a body of fabric plaited trans- 15 versely and gathered along one edge, means for anchoring the gathered edge of said body to said straight frame member midway of its ends, said body being spread fan-like about said frame and secured along its end 20 edges to said straight member, and about its periphery to said curvilinear frame member.
6. In a shade for a window of the character described, the combination of a semi-circular frame consisting of straight and 25 curvilinear members connected together at their ends, a body of fabric plaited transversely and gathered along one edge, means for anchoring the gathered edge of said body at a point midway between the ends 30 of said straight frame member, said body being spread fan-like about said frame and secured at its end edges to said straight frame member on opposite sides of its center, and means for attaching the intermediate 35 plaits to said curvilinear frame member.
7. In a shade for a window of the character described, the combination of a frame consisting of straight and curvilinear members, a body of shade fabric plaited and 40 gathered along one edge in fan-like form, a series of holes formed in the plaits at opposite ends thereof, a curvilinear member of relatively small radius located midway the 45 ends of said straight frame member, and adapted to engage the holes at the gathered ends of said plaits, the corresponding holes at the opposite ends of said plaits being threaded onto said curvilinear frame member.
8. In a shade for a window of the character described, the combination of a frame consisting of straight and curvilinear frame members, a body of plaited shade fabric gathered along one edge, an anchor rod of relatively small radius mounted midway the 50 ends of said straight frame member and passing through openings in said plaits at the gathered end thereof, said curvilinear frame member passing through other openings formed at the opposite ends of said 55 plaits, said body being parted to form separate body sections adapted to be collapsed and extended on said frame.
9. In a shade for a window of the character described, the combination of a semi-circular frame consisting of straight and curvilinear skeleton frame members, and sections of plaited shade fabric gathered along 60 one edge and anchored at the center of said straight frame member, the opposite edges of 65 said sections having sliding engagement with said curvilinear frame member whereby the same may be extended and collapsed on said frame.
10. In a shade for a window of the character described, the combination of a skeleton frame consisting of straight and curvilinear members, sections of plaited shade fabric gathered along one edge, a curved anchor rod of relatively small radius mounted midway the 70 ends of said straight frame member and passing through openings in said sections at the gathered ends thereof, said curvilinear frame member passing through other openings formed in the plaits 75 about the peripheries of said sections, and bars hinged centrally of said straight frame member and secured to said sections along their adjacent radial edges.
- Signed at San Diego, Calif., this 9th day 80 of March 1926.
